(57) **CLAIM**

The ornamental design for a foldable softbox, as shown and described.

DESCRIPTION

FIG. 1 is a perspective view of a foldable softbox showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the foldable softbox where the foldable softbox is in a folded state;

FIG. 10 is a perspective view of the foldable chuck and frame of the foldable softbox, shown separately for illustration;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 2;

FIG. 14 is a perspective view of the foldable chuck of the foldable softbox;

FIG. 15 is another perspective view thereof;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is a perspective view of the foldable chuck where the foldable chuck is in a folded state; and,

FIG. 23 is an enlarged view of portion 23 shown in FIG. 14. The dash-dash broken lines in the drawings depict portions of the foldable softbox that form no part of the claimed design. The dot-dash broken lines represent boundaries of the enlarged portions and form no part of the claimed design.

1 Claim, 23 Drawing Sheets
